ENVELOPE OR CONTAINER

Charles E. Cather and Harry W. Gordon, Worcester, Mass., assignors to United States Envelope Company, Springfield, Mass., a corporation of Maine

Application August 24, 1932, Serial No. 630,170

2 Claims. (Cl. 229—84)

The present invention relates generally to envelopes or containers, and more particularly to such articles of the locking-tongue type, i. e., where an edge of the closure flap is insertable in a slit of the envelope wall, to retain said flap in closed position. The invention involves, among other things, an improved and simplified construction and arrangement of the flap-retaining instrumentalities; in another of its aspects, the invention obtains particular advantages in envelopes or containers made from stiff relatively unbendable material such as heavy cardboard or the like,—such heavy board-like envelopes being used, for example, to inclose and protect certain articles, such as fine photographs that would be liable to damage by bending or bruising if inclosed in an envelope made of ordinary stock or material. Other and further objects and advantages of the invention will be made apparent by the following detailed description thereof, taken in connection with the accompanying drawing, in which—

Fig. 1 is a plan view of an open envelope or container embodying the invention and made from heavy stiff cardboard.

Fig. 2 shows the envelope of Fig. 1 in closed position.

Fig. 3 is a fragmentary view in end elevation, showing the manipulation of the closure flap, in the act of inserting its locking tongues.

Fig. 4 is a section on the line 4—4 of Fig. 1.

Like reference characters refer to like parts in the different figures.

Referring to the drawing, the envelope therein illustrated, made from thick stiff relatively inflexible material such as heavy cardboard or the like, may be formed in the usual way with front and back walls 1 and 2, the latter, as here shown, consisting of inwardly folded flaps 3 and 4, that are overlapped at their meeting edges in the usual fashion and adhesively secured together to provide a seam 5. The bottom of such envelope is closed by a flap 6, projecting from the front wall 1 and folded inwardly and adhesively secured to the back wall 2. At the open mouth 7 of the envelope, the material of the front wall 1 is extended to provide a closure flap 8, the latter being foldable on the line 9 to close the mouth 7, for the retention of the envelope's contents.

To make this closure effective, so that the flap 8 will be held securely in its folded-down position, without danger of springing open and exposing or releasing the contents of the envelope, the back wall 2 provides a pair of spaced slits 10, 10, which are somewhat nearer the fold line 9 than the free

edge portions of flap 8 that are aligned with said slits. That is to say, said flap 8, at least at the end portions thereof which lie opposite the slits 10, 10 is of a width such that said end portions, in the form of tongues or extensions 11, 11 of substantially the same length as the slits 10, 10, will extend downwardly past said slits when the flap 8 is folded on the line 9. Thus if the flap 8, in the act of folding on line 9, be bent or flexed, so as to shorten the distance between line 9 and the free outer edges of tongues 11, 11, said free outer edges may be entered in the slits 10, 10, whereupon the flattening out of said flap 8 in its folded-down position will project said tongues 11, 11 completely into said slits 10, 10 for the effective retention of said flap in its closed position.

Preferably, each of the slits 10, 10 is inclined upwardly in the direction of the adjacent side edge of the envelope; in other words, each slit 10, instead of being parallel to the outer free edge of its associated insertable tongue 11, is oblique to said outer free edge, so that the outer corner 12 of each tongue 11 is the portion which initially enters the slit. By thus making said initial entry with a point or corner of the tongue 11, rather than with the full width of the tongue (as would be the case if the slits were parallel to the outer free edges of the tongues), the act of inserting the tongues in the slits is greatly facilitated, since the initially entered corner 12 in each case constitutes in effect an entering wedge that materially assists the progressive entrance into the slit of the remainder of the free outer edge of the tongue, until finally the entire tongue is entered, and the flap 8 is flattened out in the closed and locked position shown in Fig. 2.

Such closure of the flap 8, in an envelope made from stiff, thick relatively unbendable material, presents this difficulty, namely, that manipulation of said flap 8, so as to register the edges of the tongues 11 with the slits 10, is impossible because the material of said flap is so stiff that any resort to temporary bending or flexing of said flap, such as avails when the envelope is made from ordinary stock, is not practical. That is to say, when the flap 8 is folded down on the score line 9, the free outer edges of the tongues 11, 11 will normally lie well below and beyond the slits 10, 10, and any attempt to enter said edges in said slits involves so much bending and distortion of the heavy material of said tongues as to make the latter dog-eared in a very short time, thus rendering them ineffective as a locking means for the closure flap, and incidentally spoiling the appearance of the

envelope and making it unfit for further use. To overcome these difficulties in an envelope made of stiff, relatively unbendable material, said closure flap 8, at or slightly inwardly of the base of the 5 tongues 11, 11, is made with one or more fold or score lines 20, running its entire width,—this enabling the flap, in the act of closing the same, to assume the position shown in Fig. 3, so that the corners 12, 12 of the tongues can, without dis- 10 tortion or breaking of the material, be readily registered with the slits 10, 10; thereupon, by pressing downwardly on the ridge thus formed at 20 when the corners 12, 12 are entered, the flap 8 can be flattened out, as such pressure gradually 15 forces the tongues into the locked position shown in Fig. 2. When so flattened out, the flap 8, offers effective resistance against any opening force applied in an upward direction at the exposed edge 19 midway of the tongues 11, 11, such force 20 tending to draw the inner side edges of the tongues into binding contact with the inner ends 18, 18 of the slits 10, 10. In order to get the flap 8 open without such binding and resistance, said flap must be seized at its opposite ends adjacent 25 the score line 20 and bent uniformly on said score line until the tongues 11, 11 are drawn clear of said slits 10, 10.

We claim:

1. An envelope of the class described, made of 30 relatively stiff inflexible material, and having a closure flap of similar material, with a score line at the juncture of said closure flap and the envelope body, to allow the closure flap, when folded down over the envelope mouth, to lie substantially flat against a wall of the envelope, said wall having cut therein a slot through which the free edge of said closure flap is given entrance, in 35 a downward direction, to the interior of the en-

velope pocket, for the locking of said flap in its closed position, said slot being closer to said score line than said free edge, and the closure flap being itself scored transversely between said score line and said free edge, to permit the entry of said free edge in said slot without distortion of the stiff inflexible material of said closure flap. 5

2. An envelope of the class described, made of relatively stiff inflexible material, and having a 10 closure flap of similar material, with a score line at the juncture of said closure flap and the envelope body, to allow the closure flap, when folded down over the envelope mouth, to lie substantially flat against a wall of the envelope, said wall 15 near the envelope mouth having cut therein a pair of spaced slots, both sloped downwardly and inwardly relative to the boundary edges of the envelope, and giving entrance to the envelope pocket, and said closure flap providing at opposite ends of its free edge a pair of spaced tongues adapted for registry with and entrance downwardly into said slots, for locking said flap in closed position, the initially-entering corners of 20 said tongues being appreciably further away from 25 said score line than the corresponding portions of said slots, and said closure flap being itself scored transversely between said tongues and said score line, to permit of bending of said flap, without distortion of its stiff inflexible material, for 30 the entry of said tongues' corners in said slots, whereby subsequent pressure on said bent flap to flatten the same procures the downward passage of said tongues through said slots into the envelope pocket, to lock said flap in closed position. 35
